UNITED STATES PATENT OFFICE.

STEPHEN A. ROAKE, OF BLOOMFIELD, NEW JERSEY.

BRIDGE CONSTRUCTION.

Application filed May 10, 1921; Serial No. 468,231.

To all whom it may concern:

Be it known that I, STEPHEN A. ROAKE, a citizen of the United States, and resident of Bloomfield, in the county of Essex and 5 State of New Jersey, have invented a new and Improved Bridge Construction, of which the following is a full, clear, and exact description.

In connection with bridge construction, 10 and more particularly bascule bridges, it is a well appreciated fact that considerable difficulty has been experienced in that virtually a supplemental workshop has to be provided at the ultimate assemblage point, 15 to insure a proper operation of the finished bridge. Thus the bridge parts, and operating mechanism have heretofore been constructed in a main plant, and the parts thus built, have been sent to the point at which 20 the bridge was to be erected. A supplemental shop has been necessary at this point to permit of the parts being fitted, one to the other, and to insure their co-operation in such a manner as to permit of the bridge 25 operating in an entirely satisfactory manner.

Furthermore, a bridge of this type has involved a relatively complicated construction, necessitating the use of many parts, and a consequential expense in both the construction 30 and operation of the bridge.

Aside from the difficulties aforementioned, further objections have been encountered in that a duplication of parts in the operating mechanism is often required in a bridge of 35 this type. This is to be predicated to the fact that navigable streams must be bridged by structures which are capable of being drawn or swung to a position permitting of the passage of boats on this stream. Usually 40 motors are provided which drive the operating mechanism serving to swing the bridge but in certain localities the streams are not utilized by boats to such an extent as to necessitate the operation of a draw or bascule bridge more than a few times a year. Obviously 45 in these localities a form of manual drive would be much more economical than a power driven mechanism whether the power be derived from a steam or gasoline engine or from an electric motor. On the other hand, provision must be made for a possible increase in the navigation on the stream, and consequently it is necessary to install a type of mechanism that can be 50 operated either manually or by power. Fur-

thermore, it is sometimes necessary to resort to manual operation of the bridge while repairs or renewals are being made to the power driven parts.

Entirely independent of the foregoing difficulties, it is well understood that a latch is utilized for normally preventing any movement of the bridge when it is in its closed position. This latch is retracted and the bridge is moved by the form of operating mechanism utilized. Sometimes the latch is projected during the movement of the bridge, and thus upon the bridge being swung to its closed position the latch extends beyond the body of the bridge and, as a result, is in danger of striking against the abutment, thereby causing a great deal of damage of the bridge parts. Furthermore, if a binding of the latch operating mechanism occurs while the bridge is being swung, damage to the parts often results due to the strain which is thrown into the latch operating mechanism upon the operation of the more powerful bridge moving mechanism.

Having these and other defects in mind, my present invention has as its primary object, the provision of a movable bridge, and more particularly a bascule bridge which may be manufactured at a main plant, and subsequently shipped to the point at which the bridge is to be erected, the parts being so arranged and constructed as to eliminate any necessity of a supplemental assemblage plant, at the point of ultimate assemblage, although a proper co-operation of the parts with each other, and satisfactory operation of the whole unit will be insured.

A further object of my invention is the provision of a device of the character specified, in which all unnecessary complications will have been eliminated, and the entire construction simplified and strengthened.

Another object of this invention is the provision of a form of operating mechanism which is equally adaptable for a manual or power drive, so that the objection on this score will have been removed.

A still further object of my invention is the construction of a movable bridge in which certain latch operating mechanism will be provided, so that primarily a projection of the latch, while the bridge is moving to its fully closed position will be obviously precluded and consequently that an operation of the latch incident to a binding

of its operating mechanism, while the bridge is being swung, will not result in any damage to the parts.

Still other objects of my invention will 5 appear in the annexed specification, taken in connection with the appended sheets of drawings, which latter present one practical embodiment of the same, and in which:

Figure 1 is a partly sectional plan view 10 of the inner end of a bridge constructed in accordance with my invention.

Figure 1^a is a similar view of the outer end thereof.

Figure 2 is an enlarged side view of one 15 of the latches.

Figure 3 is a section taken along the lines 3—3 of Figure 2.

Figure 4 is a sectional view taken along 20 the line 4—4 and in the direction of the arrows indicated in Figure 3.

Figure 5 is a side view of the device as 25 illustrated in Figure 1.

Figure 6 is a sectional view taken along the lines 6—6 of Figure 1.

Figure 7 is a sectional view taken along 30 the line 7—7, Figure 8;

Figure 8 is a section taken along the line 35 8—8, Figure 1.

Considering Figures 1 and 6, it will be 40 seen that the reference numeral 25 denotes the piers positioned adjacent to the approach of the bridge, and that 26 indicates the control station preferably arranged in proximity to the piers 25.

45 In the embodiment illustrated, it will be seen that I have illustrated a double span bridge, and main supporting girders 27, are arranged upon each of the piers 25. Each of the main girders 27 provides a bearing 28, and supporting shafts 29 extend between the bearings 28, these shafts in turn supporting the spans hereinafter more fully described.

Also cross girders 30 are arranged between 50 the supporting girders 27, and serve not only as a support for the approach girders 42, but also as a bracing medium for the supporting girders 27, and together with bracing elements 31 provide a rigid construction. Also in the embodiment illustrated, the spans are such as are utilized in railroad work in that they support cross ties 32, and rails 33, but it is obviously to be understood that the bridge may be utilized 55 for any desirable type of traffic.

With a view of simplifying the construction each of these spans comprises a pair of main girders 34 extending throughout the entire length of the span and beyond the point of pivotal support formed by the shafts 29.

To now provide means serving as a counterbalance, the ballast 35 is utilized, and the girders 34 mount, at points to the rear of their connection with the shaft 29, a series

of beams 36 which support that portion of the ballast contained in the ballast box 37.

Obviously suitable bracing 37' is provided between girders 34, and serves to inter-brace the structure, so that the entire double span 70 constitutes a rigid element. Also to provide a bumper which will prevent the span being swung beyond the position indicated in dotted lines in Figure 5, and also serve as a cushioning element for the span. Suitable stop beams are arranged between the piers 25 and adjacent the base portions thereof.

The outer end of the span, as has been shown in Figures 1^a and 5^a, co-operates with 80 a suitable type of pier 39. A shoulder of this pier supports a rest plate 40 and a steel casting 40' which is so beveled that when the outer end of the girder 34 bears against this element the span is guided into its 85 closed position in such manner that the rails 33 of the span and the rails 41 of the approach align perfectly with each other.

With respect to the inner approach shown 90 in Figures 1 and 5, it will be seen that the same comprises suitable approach girders 42, upon which the rails and their associated ties rest, it being noted that these girders are supported by a fixed support 42' at the outer end and by the cross girders 30 at 95 the inner end, and it being also noted that these girders extend above and beyond the shafts 29 so that gaps are provided at points in advance of the points of pivotal suspension of the spans, said gaps being bridged by the gap bars 43. Thus, upon the spans being swung to the position indicated in dotted lines the girders 42 and rails 41 supported thereon will constitute a fixed abutment which will be straddled by the girders 34 at points adjacent to and beyond the shafts 29. Also by virtue of the interbracing 100 43', which is provided between the girders 42 of the approach, it will be seen that the construction is materially strengthened, so that any weakness at this point is overcome.

To now provide means which will serve to swing the spans when desired, and to also provide elements of this nature which may be assembled at the point of the bridge erection without any further alteration, I utilize racks 44, one of which is associated with each of the two inner girders 34. These racks are arranged directly below the shafts 29, and have their ends equi-distant from the same, so that they form an arc of a circle having as its center, the center of the shafts. Pinions 45 are fixedly secured to the shafts 46 which latter are rotatably mounted between the two center supporting girders 27, and upon the shaft 46 being rotated it will be obvious that the pinion 45 will co-operate with the rack 44 and result in a movement of 110 115 120 125 130 135 140 145 150 the entire span.

The shaft 46 has mounted thereon, as shown in Figure 1, a gear 47. The shaft 46 may be driven from any source of power through a train of gears 48 meshing with the gear 47. The source of power that would generally be used would be an electric motor which could be positioned between the spans in the vicinity of the train of gears 48. Instead of a motor a manually operated member might be provided for raising and lowering the span.

With reference to the latch and operating mechanism therefor, which will embody the virtues set forth in the preamble of this specification, it will be noted, reference being had to Figures 1^a and 2 that a pair of dogs 64 are preferably utilized, one associated with each of the outer girders 34, and cooperating with suitable sockets 65, forming a part of the pier 39. A link 66 serves to retract each of the dogs 64, and a crank 67 keyed to the shaft 68 permits of a positive movement being effected on the part of the link 66. The shaft 68 extends transversely to the girders 34, and a lever 69 is fixed to this shaft, and a rocking of this lever in either a clock-wise or anti-clock-wise direction may be arranged by means of operating rods 70. The rear ends of the rods 70 are connected to a lever 71 similar to the lever 69, and this lever is in turn secured to a shaft 72 which is connected by means of a link 74 to a shaft 73 mounted within the bore of one of the shafts 29.

Referring to Figures 7 and 8 it will be seen that the shaft 73 is revolvably mounted in the bore of shaft 29, the ends of the shaft 73 extending beyond the ends of the shaft 29. An ear 75 has one of its ends secured to the outer end of the shaft 73. A link 76 has its outer end pivotally secured to the outer end of the ear 75, its opposite end mounting a pin 77 which extends into the arcuate slot 78 forming a part of the segments 79, secured to the shaft 80 which latter is rotatably mounted in suitable bearings.

A worm wheel 81 is also secured to the shaft 80, and a worm 82 serves to effect a rotation of the worm wheel 81, the worm 82 being in turn driven through suitable gears and shafting 83 operated by a hand wheel 84, the latter being best illustrated in Figure 7.

Assuming now that the bridge is closed, the latch projected, and that the span is to be opened, it will be seen that this may be accomplished by primarily rotating the hand wheel 84, which will drive the worm 82, and thus rotate the rod 80. No movement will result on the part of the link 76 by virtue of the arcuate slot 78 utilized. However, upon the rotation of the shaft 80, being continued, the pin 77 of the link 76 will be borne against by the end wall of the slot 78, and move the link upwardly to the position indicated in

dotted lines in Figure 13. This will obviously move the shaft 73, which movement will be transmitted to the shaft 72 and consequently effect a retraction of the latch.

The span may now be lifted by means of the operating mechanism before described. Since the shaft 73 passes through the bearings in the ends of the shaft 29 there is a possibility of the shaft 73 being rotated with the shaft 29. If such occurs the pin 77 carried by the link 76 will ride in the slot 78 to the extreme positions shown by dotted lines in Figure 13. In the downward movement of the span the pin 77 will be drawn downward in the slot 78 to the extreme position, the slot being long enough to allow for the required movement of the span. Consequently, the turning of the shaft 73 by the shaft 29 will not injure the latch operating mechanism. While the span is moving downwardly a projection of the latch will be absolutely precluded by virtue of the fact that the segments 79 will remain stationary, until the outer ends of the girders 34 had slid above the shoulder forming a part of the pier 39. Then a movement of the shaft 80 by means of the hand wheel 84 will permit the segments 79 to move to the position shown in full lines in Figure 7 and consequently depress the link 76 when the pin 77 carried thereby contacts with the rear end of the slot 78, so that the shaft 73 will be rotated to effect a projection of the latch.

Thus it will be seen that I have provided a bridge construction embodying all of the objectives set forth in the preamble of this specification, in that primarily by virtue of the simple construction of the spans and supporting girders, together with the simple but adequate and efficient arrangement of the machinery parts, a complete machinery unit is formed which may be assembled at the main plant, thus eliminating the necessity of supplemental construction and alteration at the point of ultimate assemblage, but insuring a proper co-operation of the parts with each other and a satisfactory operation of the unit as a whole.

Also, by virtue of the simple arrangement of the machinery, replacement of any of its parts may be readily made and with a minimum amount of alteration, so that perfect fitting and co-operation of the parts with one another is assured.

Furthermore, the expense of the driving mechanism utilized, which is equally adaptable for either manual or power drive, is reduced to a minimum. This form of operating mechanism although it is extremely compact and may be arranged in a space incapable of accommodating other forms of drives, provides the most efficient form of drive for use in association with the spans.

Also with respect to the latch operating elements it will be noted that all danger of

the latch being projected upon the span swinging downwardly is prevented, aside from the fact that even should the parts jamb, no damage will result to the same.

5 In this latter connection it will be seen that the safe guard is provided by virtue of the arrangement of the parts and the arcuate slot formed in the segment, as well as by the worm drive, which will prevent any 10 tendency of the shaft 80 to rotate, being transmitted to the operating wheel 84.

Furthermore, by virtue of the fact that the latches are actuated by a shaft which passes through the center of rotation of the 15 spans, complicated mechanism and the consequent liability to unsatisfactory operation are eliminated.

Finally by virtue of the inter-bracing 43' resorted to between the girders 42 constituting the approach, an extremely simple and efficient form of construction is provided which will serve to strengthen the entire assemblage.

Obviously numerous modifications of 25 structure might readily be resorted to without in the least departing from the spirit of my invention, which I claim as:

1. In bridge construction including supporting girders, hollow shafts mounted in 30 bearings carried by said supporting girders, span girders mounted on said hollow shafts, and a latch for locking the span girders in position, a latch operating mechanism comprising a secondary shaft mounted in either 35 of said hollow shafts, a plurality of levers and links for operating the latch through the secondary shaft, and members for operating the secondary shaft which are so constructed that they are not affected by the 40 rotation of the secondary shaft by the girder carrying shaft.

2. A bridge construction, including supporting girders, span girders, shafts extending through said span girders for rockingly 45 supporting said span girders with respect to said supporting girders, said shaft being formed with a bore, a secondary shaft rotatably mounted within said bore and having its ends extending beyond said first 50 named shaft, and means for moving said secondary shaft at one of its ends.

3. A bridge construction, including supporting girders, span girders, shafts extending through said span girders for revolvably 55 supporting said span girders with respect to said supporting girders, one of said shafts being formed with a bore, a secondary shaft rotatably mounted within said bore and having its ends extending beyond said first

named shaft, an ear secured to one end of 60 said secondary shaft, a link having one of its ends rockingly secured to the outer end of said ear, a segment formed with an arcuate slot, and a pin secured to the opposite end of said link and projecting through said slot.

4. A bridge construction, including supporting girders, span girders, shafts extending through said span girders for revolvably 70 supporting said span girders with respect to said supporting girders, one or more of said shafts being formed with a bore, a secondary shaft rotatably mounted within said bore, and having its ends extending beyond 75 said first named shaft, an ear secured to one end of said secondary shaft, a link having one of its ends rockingly secured to the outer end of said ear, a segment formed with an arcuate slot, a pin secured to the opposite end of said link and projecting through said slot, and means for rocking said segment.

5. A bridge construction, including supporting girders, span girders, shafts extending through said span girders for revolvably 85 supporting said span girders with respect to said supporting girders, one or more of said shafts being formed with a bore, a secondary shaft rotatably mounted within said bore, and having its ends extending beyond 90 said first named shaft, an ear secured to one end of said secondary shaft, a link having one of its ends rockingly secured to the outer end of said ear, a segment formed with an arcuate slot, a pin secured to the opposite end of said link, and projecting through said slot and means for normally preventing a rotation of said segment.

6. A bridge construction, including supporting girders, span girders, shafts extending through said span girders for revolvably 100 supporting said span girders with respect to said supporting girders, one or more of said shafts being formed with a bore, a secondary shaft rotatably mounted within said bore, and having its ends extending beyond 105 said first named shaft, an ear secured to one end of said secondary shaft, a link having one of its ends rockingly secured to the outer end of said ear, a segment formed with an arcuate slot, a pin secured to the opposite end of said link and projecting through said slot, a shaft having said segments secured to one of its ends, a worm gear also secured to said last named shaft, 110 a worm engaging said worm gear and means for rotating said worm.

STEPHEN A. ROAKE.
